UNITED STATES PATENT OFFICE.

FRANKLIN SPAULDING, OF CHICAGO, ILLINOIS, ASSIGNOR OF ONE-HALF TO GEORGE W. CHRISTOPHER, OF CHICAGO, ILLINOIS.

MOVING-PICTURE-PROJECTION MACHINE.

1,321,255.

Specification of Letters Patent.

Patented Nov. 11, 1919.

Application filed May 5, 1919. Serial No. 294,920.

To all whom it may concern:

Be it known that I, FRANKLIN SPAULDING, a citizen of the United States, and a resident of Chicago, county of Cook, and State of Illinois, have invented a certain new and useful Improvement in Moving-Picture-Projection Machines, of which the following is a specification and which is illustrated in the accompanying drawings, forming a part 10 thereof.

The object of the invention is the provision of an improved mechanism for advancing the film before the light aperture in a moving picture apparatus, by a step by 15 step or intermittent motion.

In the accompanying drawings;

Figure 1 is a side view partly in section of a portion of a moving picture projection machine illustrating the application of my 20 invention thereto;

Fig. 2 is a detail view from the left of Fig. 1, showing the cam disk, polygonal gear, and feed sprocket, and

Figs. 3, 4 and 5 are detail sections on line 25 *x—x* of Fig. 2, showing successive positions of the parts during rotation of the cam disk.

In the embodiment of the invention chosen for purposes of illustration, 10 designates the driving shaft. This shaft, by means of gears 11, drives spool driving shaft 12, and shutter 13 rotating before light aperture 14, in film gate 15. Driving shaft 10 also drives shaft 16 through intermediary gears 17, 18. Shaft 16 carries a balance wheel, as 19, and a cam disk, as 20, both rigidly secured thereon. Cam disk 20 by causing rotation of gear 21, affixed to shaft 22 bearing feed sprocket 23, causes motion of the film 24, by engagement of the spurs 23' on the sprocket with 35 the perforations in the margins of the film 40 provided for the purpose.

The present invention lies in the peculiar characteristics of the cam disk and coöperating gear and to the peculiar coaction between 45 this mechanism and the film movement.

A large portion of the face of cam disk 50 20 is a plane surface, as illustrated in Fig. 1 and while this portion of the disk is coacting with the gear, an edge of the gear lies closely adjacent and parallel thereto. In 55 this position the polygonal gear 21 is locked against movement. Cam disk 20 bears two cam surfaces each projecting from the surface of the disk. These cams are designated 25 and 26 in the drawing and are shown as

separated by a spiral groove 27, which groove is provided to allow the angle between successive edges of the gear to swing toward the disk.

Assuming the parts to be in the relative 60 positions of Figs. 1 and 2, if the cam disk be rotated in the direction indicated by the arrow of Fig. 2, cam surface 25 will first act upon gear 21, causing the initial movement as indicated in Fig. 3, by displacing an angle thereof to the right. In the position of the parts shown in Fig. 3 the angle 28 of the polygonal gear has just made its initial entrance into spiral groove 27. Immediately after this initial movement of the 70 polygonal gear, cam surface 26 comes into action as indicated, pressing downward upon the next occurring edge of the gear and continuing its rotation, as successively illustrated by Figs. 4 and 5.

Cam surfaces 25 and 26 are so designed 75 that the initial movement of gear 21 and the final portion of the movement caused by each actuation of the same by disk 20, are each much slower than is the motion thereof 80 during the middle portion of its moving period. This peculiarity of movement is very important in the actuation of films since a smooth action of the film is thereby secured and it is possible to move the film 85 much more rapidly during the middle portion of its moving period and to secure a higher average speed of movement than would be possible if the movement was uniform throughout the period. The locking 90 of the gear against movement while the plane portion of the cam disk is moving adjacent an edge of the gear is also important, since absence of movement of the film while light is passing through it is thereby insured.

The action of cam surfaces 25 and 26 upon gear 21 is a wedging action, which means that a plane perpendicular to the cam disk passing through the axis of shaft 22 would 100 cut either of these cam surfaces in a line out of parallel with said shaft. In order that the edges of the gear 21 may coact with the cam surfaces throughout their full thickness these edges are beveled as indicated in 105 Fig. 2. The result is that the edges of the polygonal gear constitute a frustum of a pyramid, as illustrated.

It will be evident that a triangular gear, instead of one of four sides, or a gear of 110

more than four sides might be used. However, the four sided gear is considered the best form to secure the peculiar coaction desired.

- 5 With the improved construction the film remains at rest during relatively long intervals and while it has a quick movement between each two consecutive intervals of rest, such movement begins very gradually as 10 and there is no tendency to tear the film as would be the case if the film were moved by a sudden jerk. Increased illumination of the picture is obtained because of the longer intervals during which light may be 15 projected through the film and the objectionable features which would otherwise be attendant upon a quick movement of the film are eliminated.

While the particular embodiment of the 20 invention chosen for illustration is a motion picture projecting machine, it will be understood that the invention is equally applicable to motion picture cameras.

I claim as my invention:

- 25 1. A moving picture apparatus comprising, a light aperture, a feed roller for intermittently moving a film in front of said aperture, a polygonal gearing for actuating said roller, and a cam disk turning on an axis at an angle to the axis of the roller 30 locking said gearing against movement during a portion of the rotation of the disk, said disk bearing two cams for operation on successive edges of said gearing for rotation 35 thereof.

2. A moving picture apparatus comprising, a light aperture, a feed roller for intermittently moving a film in front of said aperture, a polygonal gearing for actuating 40 said roller, and a cam disk having a plane surface over a portion of its face turning closely adjacent an edge of said gear, a cam projecting from said surface adapted by contact with said gear, near an angle thereof to start movement of said gear slowly 45 and a second cam adapted by contact with the succeeding angle of the gear to continue movement thereof rapidly whereby said film is intermittently fed past said aperture.

- 50 3. A moving picture apparatus comprising a feed roller, a shaft therefor, a polygonal gear on said shaft, a driving shaft arranged at right angles to said roller shaft, a cam disk on said driving shaft and having 55 plane and cam surface portions, said plane surface portion moving in a plane parallel and closely adjacent to an edge of said polygonal gear, a cam projecting from said disk adapted to contact with said edge near 60 an angle thereof to start rotation thereof

slowly, a groove in said disk for passage of the succeeding angle and a second cam on said disk adapted to contact with the succeeding edge of said gear to continue rotation thereof more rapidly whereby said feed 65 roller is given an intermittent motion, and is locked against movement between said motions.

4. In a motion picture apparatus, in combination, a pair of shafts at an angle to each other, means for driving one of said shafts, a cam disk on the driven shaft, said disk having a spiral groove flanked by projecting cam surfaces, a feed roller and a polygonal gear on the other shaft, edges of said 75 gear lying successively closely adjacent said disk, one of said cams adapted to contact with an edge of said gear and start movement thereof and the other cam surface adapted to contact with the succeeding edge 80 and complete a partial rotation of said feed roller.

5. In a motion picture apparatus in combination, a driving and a driven shaft in perpendicular relation, means for operating 85 the driving shaft, a cam disk on the driving shaft, a major portion of the face of the said disk being a plane surface, two projecting cam surfaces on the face of said disk separated by a spiral groove, a 90 gear on said driven shaft having four equal edges, the edges of said gear forming the frustum of a pyramid, said gear so placed that its successive edges lie closely adjacent the plane portion of said disk whereby the 95 cam surfaces of said disk act successively on successive sides of angles of said gear to cause successive partial rotations thereof, the angles of said gear projecting into the spiral groove during movements of the gear, and 100 a feed roller on said gear shaft.

6. In a motion picture projection machine, in combination, two shafts in perpendicular relation, means for driving one of the shafts at constant speed, a disk mounted on the 105 shaft thus driven, such disk having a flat radial surface and being channeled, the channel extending obliquely inward across the flat face of the disk from the periphery of the disk and the tongue thus formed being raised above the plane of the flat face of the disk at its free end, a polygonal wheel mounted on the other shaft, such wheel having straight peripheral edges which ride upon the said flat face of the disk in the 110 path of the said channel, and a film feeding sprocket also mounted on the last mentioned shaft.

FRANKLIN SPAULDING.
